ATTORNEY

UNITED STATES PATENT OFFICE.

JOHN J. THACHER, OF WETHERSFIELD, CONNECTICUT, ASSIGNOR TO PRATT & WHITNEY COMPANY, OF NEW YORK, N. Y., A CORPORATION OF NEW JERSEY.

FORMING ATTACHMENT FOR LATHES.

Application filed May 31, 1923. Serial No. 642,601.

This invention relates to machine tools and particularly to an improved taper attachment adapted to be used in connection with turning lathes and like machines.

5 The primary object of the invention is to provide an attachment adapted to guide the tool to perform both taper and straight turning and so adjustable that the relative depth of cut on the taper and straight portions of the work piece may be regulated as desired. In accordance with the invention, 10 a sectional guide bar is provided for controlling the cutting position of the tool slide. The two sections of the bar, as illustrated 15 in the accompanying drawing, are positioned end to end, one section being in the form of a taper bar and laterally adjustable about a pivot adjacent one end and the other section being bodily adjustable laterally toward and from the tool slide. By such 20 cooperating adjustments, the work piece may be cut to the desired taper and the adjacent straight portion thereof may be cut to the relative depth desired, such operations being entirely automatic after the bar has once 25 been properly adjusted.

Another object of my invention is to provide a taper attachment of the type stated comprising a sectional guide bar having the 30 adjacent sections thereof disposed in end to end relation, one of the said sections being in the form of a taper bar and angularly adjustable about a pivot and the adjacent section being bodily adjustable laterally 35 by means of a novel tongue and groove connection, the tool slide of course being operatively connected to the bar in a manner to be guided thereby as the tool carriage and slide are fed along the lathe bed in the 40 tooling operation.

With the above and other objects in view, my invention consists in the features of construction and operation set forth in the following specification and illustrated in the 45 accompanying drawing. In such drawing annexed hereto and forming a part of this specification, I have shown one form of my invention embodied in a turning lathe but it will be understood that the invention 50 can be otherwise embodied and that the drawing is not to be construed as defining or limiting the scope of the invention, the claims appended to this specification being relied upon for that purpose.

Referring to the figures of the drawing: 55

Figure 1 is a transverse sectional view through a lathe bed showing my improved taper attachment applied thereto.

Fig. 2 is an enlarged plan view of my taper attachment. 60

Fig. 3 is a view illustrating a piece of work turned by the attachment as adjusted to the position illustrated in Fig. 2.

Fig. 4 is a front elevation of the attachment partially in section. 65

Fig. 5 is a vertical sectional view taken on line 5—5 of Fig. 2.

Fig. 6 is a vertical sectional view taken on line 6—6 of Fig. 2.

Referring more specifically to the drawing by reference characters, 1 indicates the bed of a lathe supporting a tool carriage 2 on the longitudinally extending ways 3 thereon. A tool slide 4 mounting a tool 5 is transversely movable on a taper slide 6 70 on the carriage. A screw 7 is provided for adjusting the tool slide transversely on the taper slide. My improved taper attachment is supported on a bracket 8 adjustably mounted on a guideway 9 on the bed 75 1, a hook bolt 10 being provided for securing the bracket in place.

My improved attachment, as illustrated in the drawing, comprises a guide bar having two sections 11 and 12 mounted on the supporting surface 13 of the bracket 8. These sections are disposed in end to end relation and have raised guiding portions 11^a and 12^a 85 adapted to be engaged by guide rollers 14 and 15 on the taper slide. The roller 14 90 may be resiliently held in contact with the bar in the usual manner. The section 11 is in the form of a taper bar adjustable about a pivot clamping screw 16 adjacent the section 12. A clamping screw 17 extends upwardly through a slot 18 in the bracket and threadedly engages the end of the section 11. The section 11 therefore is adapted to function as a taper bar and the same may be angularly adjusted about the 95 pivot 16 to the desired position, graduations 19 being provided for indicating the amount of such adjustment. The screws 16 and 17 may be tightened to secure the section 11 100 in its adjusted position.

The section 12 has a tongue and groove connection with the support 13 whereby the same may be firmly supported and ad-

justed bodily as will presently be described. Secured to the support 13 by means of pins 20 and screws 21 is a rectangular block 22. The under side of the section 12 is provided with a rectangular recess 23 therein accurately formed to slidably engage over the block. The ends of the block 22 are provided with laterally extending screw threaded ears 24 having screws 25 threaded thereinto. The ends of these screws are adapted to engage against shoulders 26 formed by notching the portion 12^b of the section 12. A clamping screw 27 extends upwardly through elongated openings formed in the surface 13 and block 22 and threads into the section 12.

As illustrated in Fig. 2, the section 12 of the guide bar is positioned parallel with the axis of the work piece W which is also parallel with the ways 3 of the lathe bed. By adjusting the screws 25, the section 12 may be moved along the block 22 to adjust the section bodily toward and from the work. It will be noted, however, that in all such adjustments, the section remains parallel with the ways 3. The section may be secured in its adjusted position by means of the clamping screw 27.

In Fig. 3 of the drawing is illustrated a piece of work W turned by the attachment adjusted to the position shown in Fig. 2. The desired taper *a* may be given to the work piece by setting the section 11 to the proper angle. Also the cylindrical portion *b* of the work piece may be turned to the relative diameter desired by setting the section 12 to the proper position. It should furthermore be noted that the block 22 is parallel to the bevelled surface 28 of the section 12 whereby the said block directly receives the thrust of the tool when the same is being forced deeper into the work to form the shoulder *c* at the beginning of the cylindrical surface *b* thereon. The work piece W illustrates only one form of work which may be performed by my improved attachment, the same being capable of turning many and various relatively shaped pieces by properly adjusting the two sections of the guide bar. For example, it will be readily apparent that the work piece illustrated in Fig. 3 may be tapered in the opposite direction from that illustrated at *a* or the same may be made cylindrical, like the surface *b*, merely by adjusting the taper bar section 11.

What I claim is:

1. In combination, a support, a tool guide bar comprising two sections supported thereon in end to end relation, one section of the guide bar having a tongue and groove connection to the support, the said tongue and groove extending at an oblique angle to the operating face of the section, the other section being pivoted at a point adjacent the

first section, means whereby the first section can be adjusted along the said tongue and groove connection to bodily adjust the said section obliquely relatively to said support, and means whereby the second section can be angularly adjusted about the pivot. 70

2. In a machine tool, the combination of a bed, a tool carriage movable longitudinally thereon, a tool slide movable laterally on the carriage, a sectional guide bar extending along the bed, means operatively connecting the slide to the bar whereby the bar controls the lateral position of the slide as the carriage moves along the bed, one section of the guide bar being in the form of a taper bar and adjustable angularly about a pivot, the other section forming a co-operating extension of the taper bar and being obliquely adjustable relative thereto in a fixed direction, and means for securing 85 the sections in their adjusted positions.

3. In a machine tool, the combination of a bed, a tool carriage movable longitudinally thereon, a tool slide movable laterally on the carriage, a sectional guide bar extending along the bed, means operatively connecting the slide to the bar whereby the bar controls the lateral position of the slide as the carriage moves along the bed, one section of the guide bar being bodily adjustable obliquely in a fixed direction relative to the slide, the other section being in the form of a taper bar and adjustable angularly about a pivot adjacent the first section, and means for securing the sections in their 100 adjusted positions.

4. In a machine tool, the combination of a bed having longitudinally extending ways thereon, a tool carriage movable on the ways, a tool slide movable laterally on the carriage, a tool guide bar comprising two sections extending along the bed in end to end relation, means operatively connecting the slide to the bar whereby the bar controls the lateral position of the slide as the carriage moves along the bed, one section of the guide bar being maintained parallel with the said ways and being adjustable obliquely toward and from the slide, and means for securing the adjustable section in position. 110

5. In a machine tool, the combination of a bed having longitudinally extending ways thereon, a tool carriage movable on the ways, a tool slide movable laterally on the carriage, a sectional guide bar extending along the bed, means operatively connecting the slide to the bar whereby the bar controls the lateral position of the slide as the carriage moves along the bed, one section of the guide bar being maintained parallel with the said ways and being adjustable obliquely toward and from the slide in a fixed direction, the other section being in the form of a taper bar and adjustable laterally about a pivot adjacent the first section, and means 130

for securing the sections in their adjusted positions.

6. In a machine tool, the combination of a bed, a tool carriage movable longitudinally thereon, a tool slide movable laterally on the carriage, a sectional guide bar supported on the bed with the sections thereof in end to end relation, means operatively connecting the slide to the bar whereby the bar controls the lateral position of the slide as the carriage moves along the bed, one section of the guide bar being angularly adjustable about a fixed pivot adjacent the first section, and means for adjusting the other section in a straight line relative to the slide.

7. In a machine tool, the combination of a bed having longitudinally extending ways thereon, a tool carriage movable on the ways, a tool slide movable laterally on the carriage, a sectional guide bar supported on the bed with the sections thereof in end to end relation, one of such sections being slightly offset laterally relative to the other section and parallel with the said ways, means for bodily adjusting the said offset section obliquely toward and from the slide

in a fixed direction, and means for adjusting the other section about a pivot adjacent the first section.

8. In a machine tool, the combination of a bed having longitudinally extending ways thereon, a tool carriage movable on the ways, a tool slide movable laterally on the carriage, a bracket support on the bed laterally of the ways, a tool guide bar comprising two sections supported on the bracket in end to end relation, means operatively connecting the slide to the bar whereby the bar controls the lateral position of the slide as the carriage moves along the bed, one section of the guide bar being maintained parallel with the said ways and having a tongue and groove connection to the bracket support, the said tongue and groove extending obliquely to the said ways, and means whereby the first section can be moved along the said tongue and groove connection to bodily adjust the said section obliquely toward and from the said ways in a fixed direction.

In testimony whereof, I hereto affix my signature.

JOHN J. THACHER.
